Re. 19,999

FILING MACHINE

Original Filed May 22, 1930

UNITED STATES PATENT OFFICE

19,999

FILING MACHINE

Benjamin Grob and Theodore Grob,
West Allis, Wis.Original No. 1,949,742, dated March 6, 1934,
Serial No. 454,593, May 22, 1930. Application
for reissue March 2, 1936, Serial No. 66,776

22 Claims. (Cl. 29—76)

The present invention relates in general to improvements in the art of machine tool manufacture, and relates more specifically to improvements in the construction of power operated abrasion machines of the class ordinarily designated as filing machines.

An object of the invention is to provide an improved abrasion device which is simple and durable in general construction, and which is moreover relatively flexible and highly efficient in operation. Another object of the invention is to provide various improvements in the construction of power operated filing machines or the like, wherein the abrasive or working surfaces are movable in one direction only while engaging the work, and travel at substantially constant speed. A further object of the invention is to provide improvements in the construction of endless file transporting structures for filing machines or the like, and improved mechanism for propelling such transporting structures. Still another object of the invention is to provide improvements in driving mechanisms and work supports for machine tools, and especially for tools wherein the stretch portion of an endless band type of tool carrier is utilized to perform the work intended. Another object of the invention is to provide various improvements in the details of construction and in the mode of operating filing machines or the like, whereby the cost of construction and operation thereof are reduced to a minimum while preserving maximum efficiency. These and other objects and advantages resulting from the use of this invention, will be readily apparent from the following description.

A clear conception of an embodiment of each of the several features of the improvement, and of the mode of manufacturing, of assembling, and of manipulating filing machines, built in accordance therewith, may be had by referring to the drawing accompanying and forming a part of this specification in which like reference characters designate the same or similar parts in the several views.

Fig. 1 is a part sectional side elevation of an improved motor driven filing machine.

Fig. 2 is a front view of the improved filing machine, a portion of the frame having been broken away in order to expose internal structure to view.

Fig. 3 is an enlarged side view of a fragment of the endless carrier or chain and several of the files.

Fig. 4 is a similarly enlarged part sectional rear

view of a fragment of the chain and one of the files.

Fig. 5 is a similarly enlarged transverse section through the chain and one of the files.

Fig. 6 is a rear view of the file and chain reaction guide.

Fig. 7 is a side view of the file and chain reaction guide shown in Fig. 6.

Fig. 8 is a top view of the reaction guide shown in Figs. 6 and 7.

Fig. 9 is a top view of the reaction guide and of the support therefor, showing the file carrier and one of the files cooperating therewith.

Fig. 10 is a fragmentary top view of a portion of the work supporting table and of the adjustable plate associated therewith.

Fig. 11 is a fragmentary top view of the upper portion of the frame, showing the details of the upper wheel support.

The improved filing machine specifically shown, 20 comprises in general an endless carrier or chain 2; a series of abrasion plates or files 3 rigidly attached to selected links of the chain 2; upper and lower rotary members or wheels 4, 5 respectively providing a support for the chain 2; a main frame 25 6 supporting the wheels 4, 5 in vertically spaced relation to each other; an electric motor 7 supported upon the rear of the frame 6; and driving mechanism connecting the motor 7 with the lower wheel 5.

The endless carrier or chain 2 is of improved construction as shown in Figs. 3, 4 and 5, consisting of alternate U-shaped sheet metal links 31, 32, and intervening solid links 33 disposed between the side walls of the links 31, 32. The 35 U-shaped sheet metal links 31 are approximately double the length of the links 32, and the successive files 3 are rigidly attached to the successive long links 31 by spot welds 30 or the like. While flat files 3 have been illustrated, these 40 files may obviously be half round, triangular or of any other cross-section. The ends of the solid links 33 and the adjacent portions of the side walls of the U-shaped links 31, 32 are provided with aligned drilled holes or openings of equal diameter, and a pivot pin 34 is driven into each set of aligned openings. Each of the pivot pins 34 has a medial portion snugly but rotatably fitting the opening of the solid link 33 with which it is associated, and has opposite end portions 45 35 of reduced diameter, thus forming shoulders at the opposite end portions of the pin 34 the distance between which is slightly less than the distance between the inner surfaces of the side walls of the links 31, 32. The reduced end portion 50 55 35

35 of each pivot pin 34 coacts with the larger opening in the adjacent side wall, and the overall length of each pin 34 is approximately equal to the outside width of the links 31, 32. One of the long U-shaped links 31 may be provided with hook notches 36 in order to permit disconnection and assembly of the endless carrier.

The upper rotary member or wheel 4 is rotatably supported upon vertically adjustable slides 10 9 movably confined between parallel spacers 28 which are clamped between the main frame 6 and the auxiliary frame 26. The slides 9 are suspended from a threaded adjusting rod 10 the upper end of which has screw thread coaction 15 with a hand wheel 12. A coil spring 11 located between the hand wheel 12 and the upper extremities of the frame 6, 26, functions to resiliently urge the upper wheel 4 away from the lower wheel 5 to thereby properly tension the endless 20 carrier or chain 2.

The lower rotary member or wheel 5 is supported for rotation about a fixed axis at the lower portion of the main frame 6. The wheels 4, 5 are provided with alined circular peripheral 25 grooves within which the chain 2 travels and frictionally engages the wheels, and the tension adjusting mechanism associated with the upper wheel 4 serves to regulate the frictional driving contact. The axes of rotation of the wheels 4, 30 5 are spaced apart sufficiently to provide a substantially rectilineal stretch of files 3 of considerable length at the front of the machine, this stretch being normally movable downwardly through a central opening in a tiltable work 35 table or support 8. A reaction roller 13 rotatably supported in the lower end of the auxiliary frame 26, engages the rear of the carrier chain 2 as it leaves the upper wheel 4 and is so disposed that the chain 2 is forced forwardly beyond a 40 position of tangency relative to the wheel 4, as it proceeds toward the work support 8. An adjustable guide roller 14 likewise supported upon the lower end of the frame 26, engages the front faces of the successive files 3 and serves to steady 45 the working stretch portion of the machine.

The work table or support 8 is tiltably supported upon the frame 6 some distance below the guide rollers 13, 14, and extends entirely around the working stretch of the endless series 50 of files 3. The support 8 may be locked to the frame 6 in any desired position, and the angle of tilt of the support 8 may be accurately determined with the aid of a segment gage 18. An adjustable plate 16 which is slidably associated 55 with the work support 8, serves to minimize the gap between files 3 and the work supporting surface as the support 8 is tilted. A stationary guide 15 is formed and disposed to simultaneously engage the rear surfaces of both the chain links 60 31, 32, 33 and those of the files 3 as they enter the working zone, this guide 15 being provided with lateral ears 29 beneath the support 8, by means of which the guide is secured to a transverse plate 17 which is in turn rigidly attached 65 to the forward portion of the frame 6. The guide 15 is formed of sheet metal and is preferably of less transverse width than the files 3 above the support 8 in order to permit the filing of narrow slots and also the inside surfaces of holes in 70 pieces resting upon the support 8, the latter operation being facilitated by the disconnecting hooks 36 of the endless carrier. When the carrier is unhooked a work piece having an opening may be threaded over the guide and lowered onto 75 the table, the carrier then being again connected

and the filing on the inside of the opening can proceed.

The mechanism for transmitting motion from the electric motor 1 to the lower wheel 5 comprises a pair of belt drives one of which is associated directly with the motor 1 and the other of which delivers rotary motion directly to the wheel 5. The initial drive consists of a pair of cone sheaves 21, 25 having several sets of alined grooves providing for several speed variations, 10 and an endless V belt 20 adapted to interchangeably coact with the grooves of the several sets. The driven sheave 25 of the initial drive is secured to the sheave 23 of the final drive as shown in Fig. 2, both of the sheaves 25, 23 being rotatably supported upon a shaft supported in the lower end of a pivoted arm 22. The sheave 23 is drivingly connected with the sheave 21 secured to the lower wheel 5, by means of a V belt 19, the tension of which is capable of being 20 varied with the aid of adjusting mechanism 24 shown in Figs. 1 and 2. The weight of the arm 22 and the elements carried thereby serves to tension the belt 20 of the initial drive while permitting ready transfer of the belt 20 to any 25 set of the alined grooves in the sheaves 25, 21.

During normal operation of the machine, the motor 1 is operating to drive the wheel 5 at the speed selected, thereby causing the endless series 30 of files 3 to travel in succession around the wheels 4, 5 and to be presented in rectilineal order above the work table or support 8. Pieces of material resting upon the support 8 may then be pressed against the roughened surfaces of the files 3 which quickly abrade the presented surfaces or projections. Depending upon the position of tilted adjustment of the work table, the files 3 may be caused to cut at any desired angle, and the initial drive also permits movement of the files 3 at three different selected speeds. The 40 guide rollers 13, 14 and the relatively stiff fixed guide 15 permit the pieces to be forced against the filing surfaces with considerable pressure without undesirably deflecting the working 45 stretch of the carrier chain, and the compactness 50 of the guide 15 enables use of the device for a considerable range of purposes. The adjustable plate 16 eliminates danger of having the files 3 carry the piece of material being filed, through the central opening in the table 8, and the improved driving mechanism connecting the motor 1 and the lower wheel 5 besides being readily adjustable to produce efficient driving, is also sufficiently flexible to protect the motor against 55 shock. The hand wheel 12 may be manipulated to properly tension the chain 2 and to eliminate slippage, and the roller 14 may be adjusted to accommodate files of various thickness.

The improved chain structure is not only 60 simple and strong, but may be manufactured at minimum cost and can therefore be discarded when the files 3 are worn out, with relatively small loss. The U-shaped links 31, 32 may be formed with the aid of dies, and the spot welding 65 attachment of the files 3 to the links 31, may be accomplished without damaging the files so as to produce a rigid connection. While the pins 34 are only slipped into position during assembly of the chain and have no end heads, these pins are effectively held against endwise displacement 70 when the chain is under tension. The shoulders on the pins 34 then engage the adjacent inner surfaces of the walls of the U-shaped links 31, 32, and the pins cannot move out of the openings in 75 the intervening links 33. This feature has

proven particularly advantageous in commercial use of the invention.

From the foregoing description, it will be apparent that the invention provides a simple and durable filing machine or similar structure, which may be manufactured and operated at minimum cost. The device has proven highly efficient in operation and may be conveniently manipulated to meet a great variety of operating conditions.

0 It should be understood that it is not desired to limit the invention to the exact details of construction and to the precise mode of operation herein shown and described, for various modifications within the scope of the claims may occur 5 to persons skilled in the art.

It is claimed and desired to secure by Letters Patent:—

1. In combination, a series of files, a series of links supporting said files, said links having overlapping ends provided with alined transverse openings of equal diameter, and pivot pins having medial portions of diameter substantially equal to that of said openings and having end portions of reduced diameter, said pins connecting the successive links of said series to provide an endless file carrier.

2. In combination, a series of files, a U-shaped link secured to each of said files, other links connecting the successive U-shaped links of said series, said other links having ends disposed between the side walls of the corresponding U-shaped links and having transverse openings of the same diameter as alined openings in said side walls, and a pivot pin disposed within each set of 5 said alined openings, each of said pins having portions of reduced diameter coacting with said wall openings.

3. In combination, a series of files, and a carrier chain for said files, said chain comprising adjoining sets of links the end of one of which is disposed between side walls of the other, and which are provided with alined transverse openings of equal diameter at said intervening end and side walls, and a pivot pin disposed within 5 each set of said alined openings, said pin being of length substantially equal to the distance between the outer faces of said walls and having ends of reduced diameter coacting with the openings in said walls.

4. In combination, a series of files, a series of links supporting said files, said links having overlapping ends provided with alined transverse openings of equal diameter, and one-piece pivot pins having integral medial portions of diameter substantially equal to that of said openings and having end portions of reduced diameter, said pins connecting the successive links of said series to provide an endless file carrier.

5. In combination, a series of files, a series of links supporting said files, said links having overlapping ends provided with alined transverse openings of equal diameter, pivot pins having medial portions of diameter substantially equal to that of said openings and having end portions of reduced diameter, said pins connecting the successive links of said series to provide an endless file carrier, and means for maintaining said links under tension to prevent displacement of 5 said pins.

6. In combination, a series of files, a series of links supporting said files, said links having overlapping ends provided with alined transverse openings of equal diameter, pivot pins having medial portions of diameter substantially equal to that of said openings and having end portions

of reduced diameter, said pins connecting the successive links of said series to provide an endless file carrier, and resilient means coacting with said chain to prevent displacement of said pins.

7. In combination, a series of files, a series of links supporting said files, said links having overlapping ends provided with alined transverse openings of equal diameter, one-piece pivot pins having integral medial portions of diameter substantially equal to that of said openings and having end portions of reduced diameter, said pins connecting the successive links of said series to provide an endless file, and resilient means coacting with said chain to prevent displacement of said pins.

8. In combination, a series of files, a U-shaped carrier link attached to each of said files, other links connecting the successive carrier links, some of said other links having ends disposed between the side walls of the adjacent carrier links 20 and said files being of considerably greater width than said carrier links and projecting beyond said side walls, and a U-shaped stationary guide having a recess through which said links are movable longitudinally and also having outwardly 25 extending side flanges engageable directly with the rear of said projecting file portions, the guide width across said flanges being less than the corresponding file widths.

9. In combination, a series of files, a U-shaped 30 carrier link attached to each of said files, solid links disposed between successive carrier links and having ends disposed between the side walls of the adjacent carrier links, U-shaped connector links connecting the opposite ends of adjacent 35 solid links, said files being engageable directly with said connector links and having considerably greater width than said U-shaped links and projecting beyond the side walls thereof, and a U-shaped stationary guide having a recess through 40 which said U-shaped links are movable in succession and also having outwardly extending side flanges extending longitudinally thereof and engageable directly with the rear of said projecting file portions, the guide width across said 45 flanges being less than the corresponding file widths.

10. In combination, a series of files each having a U-shaped carrier link attached thereto, U-shaped connector links interposed between the 50 successive carrier links and engageable with the ends of said files, said files projecting laterally a considerable distance beyond all of said U-shaped links, solid links pivotally connecting the adjacent ends of the successive U-shaped links and 55 disposed between the side walls thereof, and a reversely U-shaped stationary guide having a longitudinal recess through which said U-shaped links are successively movable and also having outwardly projecting longitudinal side flanges en- 60 gageable directly with the rear of said projecting file portions, the guide width across said flanges being less than the corresponding file width.

11. In a filing machine the combination of a horizontal work table having a relatively small 65 centrally disposed vertical passageway, a frame supporting said table, a plurality of vertically spaced pulleys supported from said frame, a carrier guided on said pulleys for movement of a portion downwardly in a straight line path ex- 70 tending through said passageway, file elements fixed on the front of said carrier to provide a substantially continuous front filing surface in said path and defined between two parallel spaced vertical planes, said carrier providing side bear- 75

- ing surfaces laterally spaced between said planes and at a distance substantially less than the plane spacing, and other guide means including means rigidly supported from said frame and supporting said carrier and files against lateral displacement within said straight line path portion, said guide means at a point within the working zone of said straight line path being of lateral width less than said spacing of said planes.
- 10 12. In a filing machine, the combination of a horizontal work table having a relatively small centrally disposed passageway, a frame supporting said table, a plurality of vertically spaced pulleys supported from said frame, a chain providing flexibly pivoted links and guided on said pulleys for movement of a chain portion downwardly in a straight line path extended through said opening, file elements fixed on the adjacent links of said chain to provide a substantially continuous front filing surface in said path and defined between two parallel spaced vertical planes, said chain links providing side bearing surfaces laterally spaced between said planes and at a distance substantially less than the plane spacing, and other chain guide means rigidly supported from said frame and providing a channel shaped portion within said straight line path portion and open in the direction of said file elements, the side members of said channel portion being of an outside width defined between said vertical planes, the front faces of each of said side members providing bearings directly engaging the rear faces of said file elements.
13. In a filing machine, the combination of a horizontal work table having a relatively small centrally disposed passageway, a frame supporting said table, a plurality of vertically spaced pulleys supported from said frame, a carrier guided on said pulleys for movement of a portion downwardly in a straight line path extended through said opening, file elements fixed on the front of said carrier to provide a substantially continuous front filing surface in said path and defined between two parallel spaced vertical planes, said carrier providing side bearing surfaces laterally spaced between said planes and at a distance substantially less than the plane spacing, and other guide means rigidly supported from said frame and providing a channel shaped portion within said straight line path portion and open in the direction of said file elements, the side members of said channel portion being of an outside width defined between said vertical planes, the front faces of each of said side members providing bearings directly engaging the rear faces of said file elements.
14. In a filing machine the combination of a frame, a plurality of vertically spaced pulleys supported from said frame, a horizontal work table fixed on said frame at a level between said pulleys and providing an opening, a band guided on said pulleys for movement of a portion of said band downwardly through said opening in a straight line path, file elements fixed on said band to provide a substantially continuous filing surface in said path and defined between parallel spaced vertical planes, means adapting said band for removal and replacement through said opening and through a work piece supported on said table including elements laterally disengageable when said band is in longitudinally unstretched condition, means normally continuously stretching said band during operation of the machine, the last mentioned means being adjustable to 75 provide the slack necessary for said element dis-

engagement, and guide means preventing lateral displacement of said filing surface in said path including a guide fixed with said frame and providing vertically disposed bearing surfaces, said guide being of a width no greater than the spacing of said vertical planes.

15. In a filing machine the combination of a frame, a horizontal work table supported from said frame, said frame providing a portion extended above and over said table, a plurality of pulleys supported from said frame respectively above and below said table, a carrier guided on said pulleys for movement of a portion past said table and in a straight line path forming a working zone, file elements supported from said carrier to provide a substantially continuous filing surface within said zone and defined between two spaced vertical planes, and means substantially completely enclosing said carrier and files within said working zone except at points exposing said filing surface, said means including other guide means at the rear of said filing surface, and of a lateral width no greater than the spacing of said vertical planes.

16. In a filing machine the combination of a frame including a pair of laterally spaced side members, a base for said frame, sheaves rotatably supported between said members, driving mechanism for said sheaves disposed between said members, an endless carrier movable by said sheaves between said members, files movable by said carrier along a definite path, a horizontal work support secured to said frame and providing a vertical opening, said carrier and file path passing downwardly through said opening, and guide means restraining said carrier and files against lateral movement at the level of the upper surface of said support, said guide means at said level being of a width no greater than the lateral width of the files.

17. In a filing machine the combination of a frame, a plurality of vertically spaced pulleys supported from said frame, a horizontal work table supported from said frame at a level between said pulleys and providing a vertical opening, a carrier guided on said pulleys for movement of a portion downwardly through said opening in a straight line path, file elements fixed on said carrier to provide a substantially continuous filing surface in said path, and defined between two parallel spaced vertical planes, means adapting said carrier and files for removal and replacement through said opening and through a work piece supported on said table including elements laterally disengageable when said carrier is in longitudinally unstretched condition, means normally continuously maintaining said carrier in stretched condition, and other guide means supporting said carrier and files against lateral displacement in said path at the level of said table, said other guide means being of a width no greater than the spacing of said planes.

18. In a filing machine the combination of a frame, a plurality of vertically spaced pulleys supported from said frame, a horizontal work table supported from said frame at a level between said pulleys and providing a vertical opening, a carrier guided on said pulleys for movement of a portion downwardly through said opening in a straight line path, file elements fixed on said carrier to provide a substantially continuous filing surface in said path and defined between two parallel spaced vertical planes, means adapting said carrier and files for re-

- removal and replacement through said opening and through a work piece supported on said table including elements laterally disengageable when said carrier is in longitudinally unstretched condition, means normally continuously maintaining said carrier in stretched condition, and other guide means supporting said carrier and files against lateral displacement in said path at the level of said table, said other guide means being of a limited vertical extension above said table whereby to permit work pieces to be threaded over the guide when the carrier is removed, and of a width no greater than the spacing of said planes.
5. 19. In a filing machine the combination of a frame, a plurality of vertically spaced pulleys supported from said frame, a horizontal work table supported from said frame at a level between said pulleys and providing a vertical opening, a carrier guided on said pulleys for movement of a portion downwardly through said opening in a straight line path, file elements fixed on said carrier to provide a substantially continuous filing surface in said path, and defined between two parallel spaced vertical planes, means adapting said carrier and files for removal and replacement through said opening and through a work piece supported on said table including elements laterally disengageable when said carrier is in longitudinally unstretched condition, means normally continuously maintaining said carrier in stretched condition, and other guide means supporting said carrier and files against lateral displacement in said path at the level of said table, said table being pivoted and said other guide means being fixed with said frame to be stationary during pivotal table movement and of a width no greater than the spacing of said planes.
0. 20. In a filing machine the combination of a frame, a horizontal work table supported from said frame and providing an opening, said frame providing a portion extended above and over said table, a plurality of pulleys supported from said frame respectively above and below said table, a carrier guided on said pulleys for movement of a portion downwardly through said opening and in a straight line path forming a working zone, file elements supported from said carrier to provide a substantially continuous filing surface within said zone, and a guide for said carrier within said working zone and of a width at the level adjacent said table no wider than the filing surface of said files, said guide being unitarily removable and replaceable.
5. 21. In a filing machine the combination of a frame, a pivoted horizontal work table supported from said frame and providing an opening, said frame providing a portion extended above and over said table, a plurality of pulleys supported from said frame respectively above and below said table, a carrier guided on said pulleys for movement of a portion downwardly through said opening and in a straight line path forming a working zone, file elements supported from said carrier to provide a substantially continuous filing surface within said zone, and a guide for said carrier within said working zone and of a width at the level adjacent said table no wider than the filing surface of said files, said guide being supported from said frame to be undisturbed by the pivoting of the table and extending from beneath said table through said opening and into said working zone.
0. 22. In a filing machine, the combination of a horizontal work table having a relatively small centrally disposed vertical passageway, a frame supporting said table, a plurality of vertically spaced pulleys supported from said frame, a pivoted flexible chain guided on said pulleys for movement of a chain portion downwardly in a straight line path extending through said passageway, file elements fixed on the front of said chain to provide a substantially continuous front filing surface in said path and defined between two parallel spaced vertical planes, said chain providing side bearing surfaces laterally spaced between said planes and at a distance substantially less than the plane spacing, and other chain guide means including means rigidly supported from said frame and supporting said chain and files against lateral displacement within said straight line path portion, said means at a point within the working zone of said straight line path being of lateral width less than said spacing of said planes.
